CLAIM

The ornamental design for a hand pouch, as shown and described.

DESCRIPTION

FIG. 1 is a front perspective view of a hand pouch according to the present design.

FIG. 2 is a back perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front side elevational view thereof; and,

FIG. 8 is a back side elevational view thereof.

The broken line squares on the straps on the top side of the hand pouch and the broken line encircling the hand pouch near the front side represent stitching and are not part of the presently claimed design. The broken line area showing portions of the article in FIG. 7 also forms no part of the claimed design.
